UNITED STATES PATENT OFFICE.

WILLIAM BOEKEL, OF PHILADELPHIA, PENNSYLVANIA.

DESIGN FOR A FLOAT-BALL.

SPECIFICATION forming part of Design No. 23,499, dated July 24, 1894.

Application filed June 7, 1894. Serial No. 513,825. Term of patent 7 years.

To all whom it may concern:

Be it known that I, WILLIAM BOEKEL, a citizen of the United States, residing at Philadelphia, county of Philadelphia, State of Pennsylvania, have invented a certain new and original Design for Float-Balls, of which the following is a specification.

The accompanying drawings show two views of a float ball embodying my design.

Figure 1 is a side elevation and Fig. 2 a top plan view.

The leading features of my design are the shape and the surface configuration of the ball, comprising first a series of circular grooves or corrugations extending from each pole of the sphere about half way toward the equatorial line, and second a series of grooves or corrugations arranged at about right angles to the circular grooves and extending between the largest of said circular grooves and the equatorial line.

A is an equatorial line formed by the junction of the similar hemi-spherical portions b, b. Each of these hemi-spheres is provided with radial grooves or corrugations c forming 25 meridian lines extending from the junction or equatorial line toward the pole but terminating adjacent to the largest of a series of circular grooves or corrugations d forming 30 circles of latitude, the two series of grooves or corrugations being arranged at right angles to each other and occupying respectively the equatorial and polar zones.

What I claim is—

The design for a float-ball substantially as 35 shown and described.

In testimony whereof I affix my signature in presence of two witnesses.

WILLIAM BOEKEL.
